ATTORNEY.

UNITED STATES PATENT OFFICE.

JOSEPH OPPMAN, OF CONNELLSVILLE, PENNSYLVANIA, ASSIGNOR OF ONE-HALF
TO ABRAHAM I. DANIELS, OF CONNELLSVILLE, PENNSYLVANIA.

LICENSE HOLDER.

Application filed November 23, 1921. Serial No. 517,228.

To all whom it may concern:

Be it known that I, JOSEPH OPPMAN, a citizen of the United States, residing at Connellsburg, in the county of Fayette and 5 State of Pennsylvania, have invented certain new and useful Improvements in License Holders, of which the following is a specification.

This invention relates to holders for motor vehicle operators' license, which some 10 states require to be carried in the vehicle.

The object of the invention is to provide a device of this character constructed to retain against surreptitious removal the license. 15

Another object is to so construct such a holder as to permit the ready insertion of the license and prevent its removal without mutilating it.

With these and other objects in view, the 20 invention consists in certain novel features of construction as hereinafter shown, described and claimed.

In the accompanying drawings:—

Figure 1 represents a front elevation of 25 a license holder constructed in accordance with this invention, shown in operative position.

Fig. 2 is a vertical section thereof, the 30 holder license is inserted and with the drum or core used in connection therewith shown in elevation.

Fig. 3 is a similar view taken in a plane at right angles to Fig. 2, with the drum 35 shown in section.

Fig. 4 is a transverse section taken on the line 4—4 of Fig. 3.

Fig. 5 is a perspective view of the drum removed, and,

Fig. 6 is a vertical section showing a 40 different form of the invention.

In the embodiment illustrated in Figs. 1 to 5, a bracket 1 is shown for mounting in the vehicle in connection with which the device is to be used, said bracket being in the form of an attaching plate having laterally extending arms 2 and 3 at its opposite ends which are apertured for a purpose presently to be described. The attaching plate of the bracket is also apertured as shown at 1^a for the passage of the fasteners which are to secure the bracket to the vehicle.

The holder comprises a glass cylinder 4 open at both ends and provided at one end 55 with an annular head 5 around which is crimped the flange 7 of a closure 6, said closure being also apertured for a purpose presently to be described.

The other end of the cylinder 4 has a 60 removable flanged cap 8 closing the cylinder and this cap is apertured to register with the aperture in the bracket arm 2.

Mounted in this cylinder 4 is a reel or drum 10 of a length corresponding to the 65 length of the cylinder and which has secured to its lower end a disk like plate 11 which corresponds in size substantially to the beaded end of the cylinder 4 and is designed to be clamped between said end 70 and the closure 6, as is shown clearly in Fig. 2, to prevent all possibility of the drum or core 10 being removed. The license shown at L is designed to be mounted in the cylinder 4 between the inner face thereof and the drum 10 sufficient space being provided between these members to receive the license. The drum 10 is provided with a plurality of longitudinally spaced peripheral grooves 12, which are substantially 80 V-shaped in cross section and are intersected by longitudinally extending slots 13 in which are mounted spring pressed catches 15, one of which is located in each of the grooves 12 and which is here shown retained 85 in said groove by a wire 16 mounted in the groove. Each of these catches or pawls 15 is mounted on a plate spring 17 which operates to force the nose 18 of the pawl 90 outwardly toward the cylinder 4 to permit the license L to pass readily thereby when being inserted and which is designed to penetrate said license and hook therein when it is attempted to be withdrawn, thereby holding the license to prevent its 95 withdrawal, the space between the drum and the cylinder being such that the license only can be inserted and there is no room for insertion of a tool or implement which might be used otherwise to release the pawl. 100 The catches or pawls 15, are located in different positions longitudinally and peripherally of the drum so that they will effectively hold the license against withdrawal.

The outer or upper end of the drum or

core 10 is made truncated cone-shaped as shown at 14 to facilitate the insertion of the license.

This drum or core 10 has a bore 19 extending longitudinally therethrough to receive a bolt 20 which is of a length somewhat longer than the combined length of the cylinder and its closures and is designed to extend through the registering 10 apertures in the bracket arms 2 and 3 and those in the closure as well as through the bore 19 and is provided at its upper end with a head 21 and has its lower end threaded to receive a retaining nut 22. This 15 threaded bolt end beyond the nut is provided with a transversely extending aperture 23 to receive the shackle 24 of a pad lock 25 which is designed to lock the parts in assembled position and prevent the unauthorized separation thereof.

Should the vehicle in which this holder is mounted be stolen and the lock 25 picked or otherwise opened so that the nut 22 could be removed and the cylinder 4 slipped out 25 of the bracket arms after the bolt 20 of course having first been removed, it would be impossible for the thief to remove the license L from the cylinder owing to the retaining fingers or pawls 15 which hold it 30 in a manner above described.

This holder not only prevents the unauthorized removal of the license, but being made of glass it discloses the operator's name and number so that it may be readily seen 35 by the inspector. The form shown in Fig. 6 differs from that shown in the other figures in that the drum or core 10 is omitted and a sleeve 26 substituted which bears at its opposite ends against the inner faces of 40 the closures 6 and 8 and prevents collapse thereof when the nut 22 is screwed home. This holder is designed to hold the license shown at L, and being locked in the same manner as the device above described, will 45 prevent the removal of said license by others than skilled thieves, since the lock 25 will protect it against curious persons merely, but obviously if the lock be released, the license could be otherwise removed.

50 The preferred embodiment of the invention is disclosed in the drawings and set forth in the specification, but it will be understood that any modifications within the scope of the claimed invention may be made 55 in the construction without departing from the principle of the invention or sacrificing any of its advantages.

I claim:

1. A license holder for vehicles comprising a transparent license casing, permanently closed at one end and having a removable closure at the other, a core mounted in said casing and filling it except for a space between it and the casing sufficient to 60 receive the license, and a bolt extending 65

longitudinally through said core and closures having a head at one end and a transverse aperture at its other end to receive a padlock shackle to lock said removable closure. 70

2. A license holder for vehicles comprising a transparent license casing, means for permanently closing the casing at one end, a removable closure at the other end, and means located in said casing to permit the 75 insertion of a license and prevent its withdrawal.

3. A license holder for vehicles comprising a transparent license casing, permanently closed at one end and having a removable closure at the other, and pivoted spurs mounted in said casing to permit the insertion of a license and prevent its withdrawal. 80

4. A license holder for vehicles comprising a transparent license casing, permanently closed at one end and having a removable closure at the other, and penetrating elements so mounted in said casing as to permit the insertion of a license and prevent its withdrawal. 85

5. A license holder for vehicles comprising a transparent license casing, permanently closed at one end and having a removable closure at the other, and penetrating elements so mounted in said casing as to permit the insertion of a license and prevent its withdrawal, said elements being located in different positions longitudinally and circumferentially of the casing to insure a firm gripping of the license. 95

6. A license holder for vehicles comprising a transparent license casing, permanently closed at one end and having a removable closure at the other, a core mounted in said casing and filling it except for a space between it and the casing sufficient to receive the license, and a bolt extending longitudinally through said core and closures having a head at one end and a transverse aperture at its other end to receive a padlock shackle to lock said removable closure, and license penetrating elements carried by said core and pivoted to permit the free passage of the license when inserted 105 and to engage the license on the attempted withdrawal thereof. 110

7. A license holder for vehicles comprising a transparent license casing permanently closed at one end and having a removable closure at the other, a core mounted in said casing and filling it except for a space between it and the casing sufficient to receive the license, said core having a plurality of longitudinally spaced peripheral grooves, 120 and pivoted spurs mounted in said grooves having points extending toward the closed end of the casing operable to engage a license on an attempt to withdraw it. 125

8. A license holder for vehicles compris- 130

ing a transparent license casing permanently closed at one end and having a removable closure at the other, a core mounted in said casing and filling it except for a space between it and the casing sufficient to receive the license, said core having a plurality of longitudinally spaced peripheral grooves, longitudinal slots intersecting said grooves, and pivoted spurs mounted in said grooves at their points of intersection with said grooves and operable to engage a license when an attempt is made to withdraw it.

5 In testimony whereof, I affix my signature hereto.

JOSEPH OPPMAN.
